BOLLARD LIGHT FIXTURE

Marvin Paul Frieberg, New York, N.Y., assignor to
Exterior Systems, Inc., Fairfield, N.J.

Filed June 19, 1974, Ser. No. 480,692

Term of patent 14 years

Int. Cl. D26—03

U.S. Cl. D48—31

FIG. 2

FIG. 1

FIG. 1 is a side elevational view of a bollard light fixture showing my new design, and this is substantially the side elevational view of this light fixture from any side; and

FIG. 2 is a sectional view taken substantially on line 2—2 of FIG. 1 showing that the central light source chamber is defined by a cylindrical light transmitting material, and that it is circumscribed by a series of longitudinally spaced and substantially radial louvers, which are opaque.

The lamp is shown in broken lines in FIGS. 1 and 2 for illustrative purposes only.

I claim:

The ornamental design for a bollard light fixture, substantially as shown and described.
